INVENTOR

BY John Schless

ATTORNEY

UNITED STATES PATENT OFFICE.

MAURICE J. SCHLESS, OF NEW YORK, N. Y.

DESIGN FOR A RING OR SIMILAR ARTICLE OF MANUFACTURE.

53,535.

Specification for Design.

Patented July 8, 1919.

Application filed April 1, 1919. Serial No. 286,770. Term of patent 7 years.

To all whom it may concern:

Be it known that I, MAURICE J. SCHLESS, a citizen of the United States, residing at New York city, in the county and State of New York, have invented a new, original, and ornamental Design for a Ring or Similar Article of Manufacture, of which the following is a specification, reference being had to the accompanying drawing, forming a part thereof.

The figure is a perspective view of a finger ring showing my new design.

I claim:

The ornamental design for a ring or similar article of manufacture as shown.

MAURICE J. SCHLESS.

Witnesses:

CLARICE FRANCK,
SYLVIA LEOPOLD.
